UNITED STATES PATENT OFFICE.

OLAF E. OLESON, OF CHICAGO, ILLINOIS, ASSIGNOR TO THE EDWARD MANUFACTURING COMPANY, OF CHICAGO, ILLINOIS, A CORPORATION OF ILLINOIS.

SEPARATOR FOR STEAM AND OIL.

1,228,237.

Specification of Letters Patent.

Patented May 29, 1917.

Application filed August 24, 1914. Serial No. 858,186.

To all whom it may concern:

Be it known that I, OLAF E. OLESON, a citizen of the United States, residing at Chicago, in the county of Cook and State 5 of Illinois, have invented certain new and useful Improvements in Separators for Steam and Oil, of which the following is a specification.

My invention relates to improved steam 10 separators for separating from steam the water entrained therein, either as a result of being carried from the boiler with the steam or having been formed by partial condensation of the steam after leaving the 15 boiler.

It is well known in the art that for certain purposes, such, as for example, the operation of steam turbines, it is necessary to employ dry steam, and my invention provides 20 a construction which is effective for drying steam for this purpose.

My separator also serves to effectively remove from the steam foreign matter, such as mineral matter that may be held in suspension, so that steam delivered from the separator is not only dry but is practically pure. Furthermore, by my construction ample passageways are provided throughout the entire separator so that the steam 30 passes readily therethrough, as a result of which the separator exerts practically no back pressure upon the system.

The principles employed in my separator are applicable either to a vertical pipe line 35 or a horizontal pipe line, and while these principles of operation are the same in both cases and many of the features of construction are the same, some modification in the separator as a whole is required for a horizontal pipe line from the construction of separator used for a vertical pipe line, and I have, therefore, shown in the drawings both types of construction, so as to clearly disclose the universal applicability of my 45 separator construction to all of the varying conditions met in practice.

The several drawings illustrating my invention are as follows:

Figure 1 shows in vertical, central sectional view the separator construction employed for a vertical pipe line;

Fig. 2 is a horizontal sectional view of the parts shown in Fig. 1 taken along the line 2-2;

55 Fig. 3 is a horizontal sectional view of

the parts shown in Fig. 1 taken along the line 3-3;

Fig. 4 shows a view similar to Fig. 1, of a separator construction for use in a horizontal pipe line;

Fig. 5 is a vertical sectional view of the parts shown in Fig. 4 taken along the line 5-5, and

Fig. 6 is a horizontal sectional view 65 through the parts shown in Fig. 4 taken along the line 6-6.

Similar numerals refer to similar parts throughout the several views.

As shown in Figs. 1, 2 and 3, the separator construction for a vertical pipe line consists of a cylindrical shell 10, preferably of sheet metal, secured by rivets at its lower end to an inclosing head 11, provided at its lower end with a flange 12 to be secured to a flange coupling in the pipe line in which 70 the separator is to be used. The upper end of the shell 10 is secured by rivets, as indicated, to a flange coupling 12', which in turn is secured by bolts 13 to the lower flange of the upper head 14 of the separator. 75 The head 14 has formed upon its upper end a flange 15 to be secured to a flange coupling of the pipe line with which the separator is used. The lower head 11 has extending centrally therethrough a tubular portion 85 16, having a converging upper end 17 for directing the steam entering the separator upward and toward the axis of the separator. The separating units contained within the shell 10 are arranged in two sets, the 90 units 18 and 18' of one set being substantially identical and alternated with the units 19 of the other set, the latter units being also substantially identical. Each of the units 18 consists of a circular outer wall 20, having an outer diameter somewhat less than the inner diameter of the shell 10, and this circular wall, which is preferably of cast iron, has extending inwardly and upwardly from it four integral troughs 21 95 supporting in turn an integral circular trough 22 concentric with the axis of the separator. The upper edges of the inner ends of the troughs 21 support also the integral conical cover or cap portion 23, which 100 is flattened and closed at its upper end and extends downward at its lower end to form the outer wall of the circular trough 22. The under surface of the conical cap or cover 23 is provided with a plurality of cor-

110

rugated ridges 25 extending substantially in the same direction as the elements of the surface of the conical cap. The upper ends of the troughs 21 open into the circular trough 22, and the lower ends of the corrugated ridges 25 are disposed over the trough 22, as a result of which steam projected upward by the upper end of the inlet tube 16 is directed through the opening in 5 the circular trough 22 against the corrugated ridges 25, and any moisture in the steam is caught and held by said ridges together with the impurities held in suspension in the moist steam. The steam, separated to a greater or less degree from its 10 moisture, passes down around the circular trough 22 between the inclined troughs 21, from which point it is free to pass upward through the separator. The water and impurities collected upon the ridges 25 run 15 down these ridges and drip from them into the circular trough 22, from which they are delivered by the inclined troughs 21 through outlet openings 26 formed through the circular wall 20 of the unit 18.

The lower unit 18 is supported from the upper edge of the head 11 by a plurality of angle bars 27, so that there is an opening 28 between practically the entire edge of 20 the circular wall 20 and the upper edge of the head 11. This opening permits the water and foreign matter which accumulates in the annular space between the outer shell 10 and the circular wall 20 to pass 25 down into the receptacle formed above the head 11, owing to its conical conformation. The head 11 has an outlet connection 29 into which an outlet pipe may be threaded, and a connection 30 for receiving a gage 35 to indicate the level of the water accumulated in the head 11. The tubular portion 16 has formed on it an outwardly extending flange 31, upon which the lower edges of the brackets 32 rest, which brackets extend 40 downward from a perforated disk 33 disposed around the upper end of the tubular portion 16 in substantially horizontal position. The disk 33 has an internal diameter substantially the same as the outer diameter 45 of the upper end of the tubular portion 16, and the perforations 34 formed through this disk are of conical conformation so as to facilitate the collection and delivery through the disk of any water and foreign matter 50 that may be deposited thereon and deliver the same into the receptacle formed by the head 11. The outer edge of the disk 33 is raised slightly above the upper surface of the disk to prevent water accumulated upon 55 the disk from freely passing over the edge of the disk without going through the perforations 34. The disk 33, besides catching the moisture which may drop upon it, serves as a baffle plate to prevent free access of the 60 steam passing between the inclined troughs 65

21 to the water contained in the receptacle within the head 11. The disk 33 is held in the position desired by a plurality of bolts 35 threaded into bosses projecting outwardly from the tubular portion 16, as indicated. 70

Each of the units 19 consists of a circular wall 36, of substantially the same external diameter and thickness as the circular wall 20 of each of the units 18, and projecting inwardly from about the middle of this circular wall 36 is an upwardly extending conical wall 37, provided with a central circular opening 38, of a diameter somewhat smaller than the external diameter of the conical cap 23. The lower surface of the conical wall 37 is provided with a plurality of ridges 39 substantially parallel with the elements of the conical surface of the wall 37. The circular wall 36 has extending therethrough, just above the lower edge of the wall 37, a plurality of outlet openings 40 for discharging into the annular space between the shell 10 and the circular wall 36 any water and foreign matter that may be 80 precipitated upon the upper surface of the conical wall 37, and the ridges 39 serve to engage any moisture projected against them by the steam and facilitate the draining of said moisture and foreign matter downward and outwardly against the inner surface of the circular wall 36, from which it drains 85 downward into the receptacle formed in the lower head 11. 90

The steam passing upward from the lower unit 18, as described, has a path of larger cross-sectional area and therefore engages the under surface of the conical wall 37 at a much decreased velocity, and the ridges 39 are effective in separating from the steam the moisture and foreign matter which may be carried thereby, and this steam is then deflected toward the center of the separator and upwardly through the opening 38, after which it again engages one of the units 18, 100 and then in turn one of the units 19, and so on to the top of the separator. The outer circular walls of the units 18 and 19 together form a circular shell inside of the outer shell 10, so that the clearance space between them forms a receiving passage for the water which is protected from the steam passing upward through the separator and thus the steam is prevented from taking up any of said water or oil and water and carrying it through the separator and delivering the same from the outlet opening of the separator. The various units 18 and 19 are held in the position referred to by vertical bolts 41 extending through suitable bosses formed on the inner surfaces of the circular walls 20 and 36, the lower ends of these bolts being threaded into bosses formed in the lower head 11, and provided at their upper ends with nuts to secure this result. 110 115 120 125 130

The upper unit 18' has secured upon its upper edge an upwardly extending circular screen 42, secured in place by means of ears extending inwardly under the nuts on the upper ends of the bolts 41, and this screen serves to catch the remaining moisture and foreign matter that may be contained in the steam passing upward from the unit 18', and serves also to prevent the steam from entering the upper end of the annular space just inside of the shell 10, and circulating through said space in contact with the separated water. The upper conically shaped head 14 has projecting downwardly therefrom a circular flange 43 of considerably smaller diameter than the screen 42 for engaging and preventing the free escape of the steam from within the screen 42, so that the traces of moisture and foreign matter which may still be carried by the steam may have opportunity to be engaged by the screen and the lower surface of the head 14. Ample space is provided, however, between the lower edge of the flange 43 and the outer surface of the cap of the unit 18' so that the steam, after having been thus brought into contact with the screen 42 and the inner surface of the head 14 may readily escape into the discharge opening formed in the head 14.

In the construction shown in Figs. 4, 5 and 6, the arrangement of the separating units 18^a, 19^a and 18' and the construction of these units is similar to the arrangement and construction of the units 18, 19 and 18' above described, with the exception that these units are contained in a casing and have a modified construction, permitting the use of the separator in a horizontal steam pipe line instead of a vertical pipe line. The operation of the separating units in this construction is the same as above described, as a result of which it will only be necessary to point out the features of construction which are different from the construction above described. This modified construction of separator consists of a vertical cylindrical casing 44, provided at opposite sides of its upper end with flange couplings 45 and 46 for connecting the separator in the horizontal pipe line, the flange 46 having extending through it into the cylindrical receptacle or casing an inlet opening 47, while the flange 45 has extending through it a similar outlet opening 48.

As shown more clearly in Figs. 5 and 6, each of the units 19^a and 18^a has formed thereon a vertical wall 19^b and 18^b substantially midway between its center and its outer cylindrical surface, and each of these vertical walls has formed on its upper edge a tongue extending into a corresponding groove formed in the lower edge of the similar vertical wall immediately above it, so that the several vertical walls carried by

said units may readily be brought into and maintained in alinement with each other to form a continuous vertical wall between the inlet opening 47 and the vertical axis of the separator. The vertical wall 18^b extends so that its upper edge is substantially in the plane of the top of the casing 44 and is engaged by parallel flanges 49 and 50 extending downward from the cap 51 employed to close the upper end of the casing 75 in the manner indicated. The several vertical walls referred to constitute a practically continuous wall or partition across the casing 44, with an uninterrupted opening between them and the side of each unit 80 nearest to the inlet opening 47, as a result of which steam entering said opening is directed downward through said uninterrupted passageway to the bottom of the separator where it enters the lowermost separating unit 52, which is circular in conformation and provided with a wall forming a continuation of the outer circular wall of the units 18^a and 19^a. The unit 52 is provided with a perforated bottom 53, which facilitates ready passage of moisture and impurities collected in said unit through the bottom thereof into the receptacle provided below said bottom in the lower spherical end of the casing 44, and a threaded connection 54 is provided in the lower end of the casing 44 to drain from the casing any water or oil and impurities that may thus be collected.

The faces of the vertical partitions 18^b, 18^c and 19^b with which the entering steam comes in contact, are provided with inclined ridges, as shown in Fig. 5, each ridge having an upper surface in a plane substantially parallel with the axis of the inlet and outlet openings and a lower surface inclined to said axis. These inclined ridges start from substantially the middle line of the vertical walls or partitions 18^b, 18^c and 19^b and extend outwardly toward the outer edge of the walls, being constructed so as to be continuous across the joints between the walls of adjacent units. These provide a means for engaging a considerable part of the moisture that may be carried by the steam entering the separator and draining it downward and to the outer edges of the walls, together with the impurities that may be carried with said moisture. The upper edge of the lowermost unit 52 is provided with two cups 55 for receiving the moisture and impurities thus collected which drain down from the outer edges of the said walls into said cups and through the outlet openings in the cylindrical wall of the unit 52, 125 extending into said cups. The steam thus directed into the unit 52 passes upward into the separator units 19^a and 18^a alternately and finally through the uppermost separating unit 18^a, from which it is discharged 130

from the separator through the outlet opening 48. The outer cylindrical walls of the separating units are of somewhat smaller external diameter than the internal diameter of the casing 44, and these walls have formed on them projecting lugs engaging the inner surface of the casing 44 to hold the separating units in substantially central position in said casing, thus forming a circular clearance space between the outer walls of the separating units and the casing for receiving the separated water and impurities and directing them downward into the receptacle therefor in the lower part of the casing 44.

As a result of the construction described in connection with Figs. 4, 5 and 6, it will be understood that the moisture separated from the steam by the vertical wall, consisting of the several sections 18^b, 18^c and 19^b, is prevented from coming in contact with the steam passing around the lower edge of said vertical wall in the unit 52, which prevents the partially dried steam from again becoming moist before it engages the lowermost separating unit 19^a.

While I have shown my invention in the particular embodiment above described, I do not, however, limit myself to these particular constructions, as I may employ any equivalents thereof known to those skilled in the art without departing from the spirit of my invention.

What I claim is:—

35 1. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall, open at its upper end and closed at its lower end, a tubular wall located inside of and separated from said casing, each unit having an outlet opening or openings through said tubular wall to deliver water and foreign matter into the space between said tubular wall and said casing, and means in each of the units of the first series for conducting water and foreign material from the separating surface thereof to the outlet opening of said unit.

55 2. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall, open at its upper end and closed at its lower end, a tubular wall located inside of and

separated from said casing, each unit having an outlet opening or openings through said tubular wall to deliver water and foreign matter into the space between said tubular wall and said casing, the lower surface of each conical separating wall being provided with ridges extending substantially parallel with the elements of said conical surface, and means in each of the units of the first series for conducting water and foreign material from the separating surface thereof to the outlet opening of said unit.

3. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall, open at its upper end and closed at its lower end, a tubular wall located inside of and separated from said casing, each unit having an outlet opening or openings through said tubular wall to deliver water and foreign matter into the space between said tubular wall and said casing, a horizontal perforated wall located near the bottom of the casing for preventing ready contact of the steam entering the separator with the separated water, and means in each of the units of the first series for conducting water and foreign material from the separating surface thereof to the outlet opening of said unit.

4. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall, open at its upper end and closed at its lower end, a tubular wall located inside of and separated from said casing, each unit having an outlet opening or openings through said tubular wall to deliver water and foreign matter into the space between said tubular wall and said casing, a receptacle formed in the lower part of said casing for receiving the separated water and foreign matter, communicating passages between the space surrounding the circular walls of said units and said receptacle, and means in each of the units of the first series for conducting water and foreign material from the separating surface thereof to the outlet opening of said unit.

5. In a steam separator, the combination of a cylindrical casing, two series of separating units disposed alternately one above

- the other in the casing upon a common vertical axis, the units of one series each having a conical separating wall closed at its upper portion and open at its lower portion, and each of the units of the other series having a conical separating wall closed at its lower portion and open at its upper portion to engage the moisture contained in the steam passing through the separator, devices for conducting the separated moisture to the lower portion of the casing, said casing having an outlet opening for each of the first mentioned series of units, and means in each of the units of said first series for conducting water and foreign material from the separating surface thereof to the outlet opening of said unit. 6. In a steam separator, the combination of a cylindrical casing, two series of separating units disposed alternately one above the other in the casing upon a common vertical axis, the units of one series each having a conical separating wall closed at its upper portion and open at its lower portion, and each of the units of the other series having a conical separating wall closed at its lower portion and open at its upper portion to engage the moisture contained in the steam passing through the separator, devices for conducting the separated moisture to the lower portion of the casing, each of the conical separating walls having ridges for engaging the moisture and directing it to the outer and lower portion of said wall, said casing having an outlet opening for each of the first mentioned series of units, and means in each of the units of said first series for conducting water and foreign material from the separating surface thereof to the outlet opening of said unit. 7. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall open at its upper end and closed at its lower end, a tubular wall located inside of and separated from said casing, each unit having an outlet opening or openings through said tubular wall to deliver water and foreign matter into the space between said tubular wall and said casing, and a tubular screen extending vertically from the upper edge of said tubular wall, a head inclosing the upper end of said casing, and a tubular flange of smaller diameter than said screen projecting downwardly from said head. 8. In a steam separator, the combination of a cylindrical casing, a cylindrical tubular wall inside of said casing and separated therefrom, a separating wall carried within said tubular wall for engaging the moisture in the steam passing through the separator and delivering said moisture to the space between said tubular wall and said casing, said separating wall having steam passages between it and said tubular wall, and means for conducting water and foreign material from the separating surface of said separating wall to the space between said casing and said tubular wall. 9. In a steam separator, the combination of a cylindrical casing, a cylindrical tubular wall inside of said casing and separated therefrom, and a separating wall carried within said tubular wall for engaging the moisture in the steam passing through the separator and delivering said moisture to the space between said tubular wall and said casing, ridges formed on the under surface of the separating wall for increasing the surface of engagement of said wall with the steam passing through the separator, said separating wall having steam passages between it and said tubular wall, and means for conducting water and foreign material from the separating surface of said separating wall to the space between said casing and said tubular wall. 10. In a steam separator, the combination of a cylindrical casing, a cylindrical tubular wall inside of said casing and separated therefrom, and a separating wall carried within said tubular wall for engaging the moisture in the steam passing through the separator and delivering said moisture to the space between said tubular wall and said casing, a lower head for said casing having an inlet opening therethrough, a horizontal partition carried by the upper end of said head, said separating wall having steam passages between it and said tubular wall, and means for conducting water and foreign material from the separating surface of said separating wall to the space between said casing and said tubular wall. 11. In a steam separator, the combination of a cylindrical casing, a cylindrical tubular wall inside of said casing and separated therefrom, and a separating wall carried within said tubular wall for engaging the moisture in the steam passing through the separator and delivering said moisture to the space between said tubular wall and said casing, a lower head for said casing having an inlet opening therethrough, a horizontal partition carried by the upper end of said head, said separating wall having steam passages between it and said tubular wall, and means for conducting water and foreign material from the separating surface of said separating wall to the space between said casing and said tubular wall. 12. In a steam separator, the combination

of a cylindrical casing, a cylindrical tubular wall inside of said casing and separated therefrom, and a separating wall carried within said tubular inner wall for engaging
5 the moisture in the steam passing through the separator and delivering said moisture to the space between said tubular wall and said casing, an upper head for said casing having a downwardly extending circular
10 flange and provided with an outlet opening for the steam passing through the separator, said separating wall having steam passages between it and said tubular wall, and means for conducting water and foreign material
15 from the separating surface of said separating wall to the space between said casing and said tubular wall.

13. In a steam separator, the combination of a casing, two series of separating units disposed alternately one above the other in the casing, the units of one series each having a conical separating wall closed at its upper portion and open at its lower portion, and each of the units of the other series having a conical separating wall closed at its lower portion and open at its upper portion to engage the moisture contained in the steam passing through the separator, a circular trough located below the lower edge
30 of each of the conical walls of said first series of units, and a trough or troughs extending transversely of the casing from said circular trough for directing the separated moisture toward the side wall of the casing.
35 14. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall open at its upper end and closed at its lower end, a tubular
40 wall located inside of and separated from said casing, and each unit having an outlet opening or openings through said tubular wall to deliver water and foreign matter into the space between said tubular wall and said casing, and a tubular screen extending vertically from the upper edge of said tubular wall, a head inclosing the upper end of said casing, and a tubular flange of smaller diameter than said screen projecting downwardly from said head, said upper head forming the outlet connection of said separator, and a second head inclosing the lower end of said casing and constituting the inlet connection of said separator.
45 15. In a steam separator, the combination of a casing, separating units disposed in the casing in two series, the units of one series alternating with the units of the other series, each of the units of one series having a circular trough disposed below the lower edge of its conical separating surface, and a trough or troughs connecting said circular trough with the outlet opening or openings through said tubular wall.

16. In a steam separator, the combination

of a casing, separating units disposed in the casing in two series, the units of one series alternating with the units of the other series, each of the units of one series having a conically shaped separating wall closed at its upper end and open at its lower end, and each of the units of the other series having a conical separating wall open at its upper end and closed at its lower end, a tubular wall located inside of and separated from said casing, each unit having an outlet opening or openings through said tubular wall to deliver water and foreign matter into the space between said tubular wall and said casing, and a tubular screen extending vertically from the upper edge of said tubular wall, a head inclosing the upper end of said casing, and a tubular flange of smaller diameter than said screen projecting downwardly from said head, said upper head forming the outlet connection of said separator, and a second head inclosing the lower end of said casing and constituting the inlet connection of said separator.

17. In a steam separator, the combination of a casing, separating units disposed in the casing in two series, the units of one series alternating with the units of the other series, each of the units of one series having a conically shaped separating wall closed at its upper end and open at its lower end, and each of the units of the other series having a conical separating wall open at its upper end and closed at its lower end, a tubular wall located inside of and separated from said casing, each unit having an outlet opening or openings through said tubular wall to deliver water and foreign matter into the space between said tubular wall and said casing, and a tubular screen extending vertically from the upper edge of said tubular wall, a head inclosing the upper end of said casing, and a tubular flange of smaller diameter than said screen projecting downwardly from said head, said upper head forming the outlet connection of said separator, and a second head inclosing the lower end of said casing and constituting the inlet connection of said separator, and a horizontal perforated wall carried by said second head.

In witness whereof, I hereunto subscribe my name this 17 day of August, A. D. 1914. 110
OLAF E. OLESON.
